HEEL-SEAT-FITTING MACHINE

Abram Moskowitz, St. Louis, Mo., assignor to
 United Shoe Machinery Corporation, Paterson,
 N. J., a corporation of New Jersey

Application November 14, 1932, Serial No. 642,493

22 Claims. (Cl. 12—31.5)

This invention relates to the manufacture of shoes and is illustrated as embodied in a heel-seat fitting machine.

When soles are fitted for the reception of wood heels prior to the attachment of such soles to shoe uppers, considerable difficulty has been experienced in locating accurately the heel-breast line of the sole. Accordingly, when the heel-seat portions of the soles are reduced before the soles are attached it is sometimes the practice to form a tongue shaped to receive the attaching face of a Louis heel and to leave tabs at the opposite lateral portions of the base of the tongue. Then, after the sole has been attached to the shoe, a hand operator trims the tab to form heel-breast-receiving shoulders against which the forward edge of the lip of the breast of the positioned heel abuts; or the tabs are skived to provide a pair of tabs such as are disclosed in United States Letters Patent No. 1,702,382, granted February 19, 1929 on an application filed in the name of Henry B. Gorman. The skived tabs are laid on the projecting lip of a Louis heel after it has been secured in position upon the shoe, after which the heel-breast-covering flap is cemented to the breast of the heel. By trimming the attached sole, as above described, the hand operator is able quickly to complete the heel-seat-fitting operation after the sole has been attached to the shoe and the expense of such operation is materially reduced.

It is an object of this invention to provide an inexpensive machine which will quickly and effectively prepare the heel ends of unattached soles for the reception of heels. Another object of the present invention is to provide a machine which will form on an unattached sole, a tongue shaped to fit the attaching face of a Louis heel and a pair of tabs, which after the sole has been attached to the shoe, may be either trimmed to abut against the lip of the heel or may be skived to overlap such lip as above described.

With the above objects in view the illustrated machine, in accordance with a feature of the invention, is provided with members constructed and arranged to engage the opposite sides respectively of a positioned sole and mounted for relative movement to distort the heel seat portion of the sole, and a cutter or die having heel seat reducing and shoulder forming cutting edges, the die being movable in a path disposed at a substantial angle to the plane of the sole to reduce the heel seat portion of the sole and to form heel breast receiving shoulders upon the sole.

The illustrated sole-distorting members are of

concave and convex form, respectively, and cooperate effectively to flex or distort and to clamp the heel end of the sole preparatory to severing the same. The heel seat reducing edge of the illustrated cutter or die is U-shaped and cooperates with a correspondingly shaped shearing edge formed on the convex distorting member to trim the margin of the heel end of the sole by a beveling cut, and the shoulder forming edges which extend laterally from opposite sides of the U-shaped cutting edge are inclined to the plane of such edge and are constructed and arranged to cooperate with notches formed in the convex distorting member thereby to sever from the sole the portion cut by the U-shaped cutting edge.

With the above and other objects and features in view, the invention will now be described with reference to the accompanying drawings and pointed out in the claims.

Fig. 1 is a perspective view of the illustrated machine;

Fig. 2 is a side elevational view of the machine having a sole positioned therein;

Fig. 3 is a transverse sectional view taken along line III—III of Fig. 2 and showing the relative positions of the parts of the machine and the sole after the heel end of the sole has been distorted but before the sole has been severed;

Fig. 4 is a transverse sectional view of the machine taken along line IV—IV of Fig. 2 and illustrating the relative positions of the parts of the machine and the sole just after the sole has been severed;

Fig. 5 is a perspective view of a slightly modified form of machine which may be used effectively for preparing the heel ends of unattached soles for the reception of Cuban heels;

Fig. 6 is a perspective view of the rear portion of an unattached sole trimmed in the machine illustrated in Figs. 1 to 4; and

Fig. 7 illustrates the sole shown in Fig. 6 after it has been trimmed by an operator to form heel-breast-receiving shoulders against which the forward lip of a Louis heel abuts.

The illustrated machine is described with reference to the fitting of heel seats of unattached soles for the reception of Cuban and Louis heels. In preparing shoes for the reception of Louis heels it is sometimes the practice, as disclosed in the above-mentioned United States Letters Patent No. 1,702,382, to trim the margins of the rear end of a sole 18 to provide a tongue portion 20 (Fig. 6) and to form at the base of the tongue a pair of tabs 22. After the sole 18, which has been trimmed in the machine, has been attached

to the shoe, an operator accurately determines the position of the breast line 24 of the sole by placing a Louis heel on the shoe and either skives the tabs widthwise and lengthwise by the use 5 of a hand knife and lays such tabs upon the breast of the heel or cuts off the tabs 22 (Fig. 7) to form heel-breast-receiving shoulders 26 against which the forward edge of the lip of the heel abuts.

10 In order to form the tongue 20 and the tabs 22 in the illustrated machine, the sole is placed flesh side downwardly upon a work-supporting table 28 the rear portion of the sole overlying an opening 30 (Fig. 1) formed in the table. 15 The sole 18 is positioned upon the table 28, relatively to a convex member or block 32 around which the heel end of the sole is flexed or wrapped by a concave member 34 preparatory to moving a die 36 into engagement with the convex member 32 to trim the margin of the heel end of the sole, by a back gage 38 (Figs. 1 and 2) shaped and arranged to engage the rear end of the sole. The back gage 38 comprises a forward cylindrical surface 40 having a curvature corresponding generally to the rear part of the heel end of the sole and is provided with a pair of slots 42 shaped to receive upstanding pins 44, respectively, carried by the table 28; which pins guide the gage 38 for purposes of adjustment lengthwise of the table. The back gage 38 is also provided with a central slot 46 through which passes a threaded pin 48 secured to the table and constructed to receive a wing nut 50 of suitable size to clamp the gage 38, after it has been properly adjusted, 35 to the table 28. When the rear end of the sole engages the cylindrical surface 40 the sole is accurately positioned lengthwise and the rear end of the sole is positioned widthwise.

To insure that the sole is properly positioned widthwise upon the table 28, a plate 52, which is 40 adjustable relatively to the table through the use of screw and slot connection 54, is mounted upon the table and is arranged to engage a side of the sole immediately ahead of the breast line 24 of the same. To assist the operator in readily setting the back gage 38 lengthwise of the table to accommodate different lengths of soles such gage is provided with a mark 56 which may be placed in registry with one of a plurality of index marks 58 cut in the sole-supporting face of the 45 table 28.

The table 28 is mounted upon four rods 60 secured to a stationary frame 62 to which the convex member 32 is attached. The block 32 comprises a convex surface or dome portion 64 from the lower end of which extends a step 66. The step 66 includes a shearing edge 68 and is constructed and arranged for engagement with the lower corner 69 (Fig. 1) of the concave member 34 when a sole is not positioned in the machine and the die is moved to a lowered position. The step 66 also comprises a vertically disposed face 72, along which a U-shaped cutting edge 74 of the die 36 moves to trim, by a shearing cut, sole material clamped between the convex and concave members 32 and 34. The dome portion 64 of the block 32 has the general form of an ellipsoid and, as above stated, cooperates with a concave or dished surface 76 (Fig. 1) of the member 34 to depress the margin of the heel end of the sole with respect to the central portion of the heel end as the member 34 is moved downwardly with the die.

The die 36 is provided with a laterally projecting plate portion 78 bored to receive a pair of

bushings 80 constructed and arranged respectively to receive a pair of die-guiding rods 82 which are secured to the stationary frame 62.

The die 36 is also provided with a pair of opposed wing portions 84, the cutting edges 86 of which extend laterally of and downwardly from the U-shaped cutting edge 74 and are spaced from the ends of the cutting edge 74. The cutting edges 86 are so arranged that upon downward movement of the die 36 they engage notches 88 of the convex block 32 and form the tab 22 at each side of the tongue and remove the chip cut by the U-shaped cutting edge 74 from the sole.

The concave member 34, which is included within the U-shaped cutting edge 74 and is mounted for sliding movement relatively to the die 36 along a guideway 90 of the die, is secured to pins 92 movable along a cylindrical recess formed in the die 36 and provided with heads 94 (Fig. 4) which limit the downward movement of the concave member 34 relatively to the die 36. Springs 96 surrounding the pins 92 and the upper and lower ends of each of which engage the die 36 and the concave member 34, respectively, normally force the concave distorting member downwardly relatively to the die 36 until the heads 94 engage a shoulder 98 of the die.

It will be noted that when the die 36 is in its raised position (Fig. 1) the concave member 34 projects slightly below the U-shaped cutting edge 74. It will, therefore, be clear that when the die 36 is lowered, the concave member 34 will co-operate with the dome portion 64 of the convex block 32 effectively to distort the rear portion of the sole before the cutting edge 74 of the die 36 which operates in shearing relation with the edge 68 of the block 32 and which slides along the vertical face 72 of the block, trims the marginal portion of the sole.

In order to cut the chip formed by the U-shaped die 36 in two parts so that material removed from the sole will readily drop from the machine at the end-trimming operation, the illustrated die 36 is provided with a cutting edge 100 which projects downwardly and rearwardly from the rear of the cutting edge 74 and cooperates with a rear notch 102 (Fig. 1) formed at the back of the convex block 32 to cut the chip in half.

The die 36 may be reciprocated along the rods 82 by any suitable device, such for example as the treadle operated mechanism disclosed in United States Letters Patent No. 1,697,243, granted January 1, 1929, on an application filed in the name of Jonas or by any other suitable press.

The table 28 may be secured to or may be 130 slidably mounted upon the rods 60. When the table is slidably mounted upon the rods 60 it is supported and is normally held in a raised position by springs 104 which surround the rods. The springs 104 permit the table 28 to be depressed as the sole is being operated upon to relieve the strain upon the sole in the vicinity of the breast line of the same during the sole-distorting and trimming operation.

In operating upon soles which are to receive Cuban heels it is desirable that heel-breast-receiving shoulders be formed at the forward end of the U-shaped cut made by the die 74 in order that the forward end of the U-shaped cut, which in the case of Cuban work is not covered by a breast flap as in Louis work, will not be visible in the finished shoe. The illustrated machine may be slightly modified, as illustrated in Fig. 5, in order effectively to trim the heel seats of soles

for the reception of Cuban heels. Such a machine is similar to that above described but is provided with cutting edges 106 extending laterally of and downwardly from the forward ends of the U-shaped cutting edge 74 and shaped and arranged to cooperate with notches 108 of the convex block 32 to form heel-breast-receiving shoulders upon the sole.

In order to perform the sole-trimming operation the operator positions the sole 18, flesh side down and breast flap 21 turned back, upon the table 28 by the use of gages 38 and 52. The die 36, which is normally held in a raised position is then caused to move downwardly whereupon the concave member 34 cooperates with the dome portion 34 of the block 32 to flex the rear end of the sole as shown in Fig. 3. Upon continued downward movement of the die 36 the U-shaped cutting edge 74, which slides in contact with the face 72 of the concave block, severs the margin of the rear part of the sole by a beveling cut. As the U-shaped cutting edge 74 moves past the U-shaped shearing edge 68 the cutting edges 86 enter the notches 88 respectively, to remove portions of the chip from the sole and to form the tabs 22.

The shape of the notches 88 and 108 may be such that the cutting edges 86 and 106 respectively of the die do not actually strike against the block 32 but sever sole material which is supported at opposite sides of the notches. Such an arrangement preserves the cutting edges 86 and 106 of the dies.

Having thus described my invention, what I claim as new and desire to secure by Letters Patent of the United States is:—

1. A heel-seat fitting machine having, in combination, members constructed and arranged to engage the opposite sides respectively of a sole and mounted for relative movement in a predetermined path, means for effecting relative movement of the members to flex the heel-seat portion of the sole, and a die, said die and said members being mounted for relative movement, the die being provided with a cutting edge shaped and arranged to reduce the flexed heel-seat portion of the sole and to form heel-breast receiving shoulders on the sole during relative movement of the die and the members.

2. A heel-seat fitting machine having, in combination, members mounted for relative movement, means for effecting relative movement of the members to flex the heel-seat portion of a sole, a die provided with a cutting edge of the general shape of the letter U and having a pair of cutting edges which extend transversely of the U, and means for moving the die relatively to the members to reduce the heel-seat portion of the sole as well as to form heel-breast receiving shoulders upon the sole.

3. A heel-seat fitting machine having, in combination, concave and convex members one of which is mounted for movement relatively to the other, a die mounted for movement relatively to the members and having a cutting edge shaped and arranged to reduce the heel-seat portion of the sole and to form heel-breast receiving shoulders thereon, and means for moving one of the members relatively to the other to distort the heel-seat portion of the sole of the shoe and for moving the die relatively to the members to reduce the heel-seat portion of the sole and to form heel-breast receiving shoulders thereon.

4. A heel-seat fitting machine having, in combination, members for engaging opposite sides re-

spectively of a sole, a die provided with a cutting edge having the general shape of the letter U and having cutting edges extending transversely of the U, and means for moving one of the members and the die relatively to the other member in order first to distort the heel-seat portion of the sole and then to cause the knife to cooperate with said other member to reduce the heel-seat portion of the sole and to form heel-breast receiving shoulders thereon.

5. A heel-seat-fitting machine having, in combination, a member provided with a convex face, a member having a concave face and mounted for movement relatively to the first named member to cause the convex and the concave faces to distort the heel seat portion of a sole, and a cutter provided with heel seat reducing and heel breast shoulder forming edges and movable in a path disposed at substantially right angles to the plane of the sole to trim material from the margin of the distorted heel seat portion of the sole thereby shaping it to a shape suitable for the reception of a heel.

6. A heel-seat-fitting machine having, in combination, convex and concave members, a die provided with a U-shaped cutting edge and a pair of heel breast shoulder forming edges, and means to effect relative movement of the die and one of the members on one hand and the other member on the other hand to distort the heel seat portion of a sole and then to reduce the same by a beveling cut inclined to the plane of the sole and to form heel breast receiving shoulders on the sole.

7. A heel-seat-fitting machine having, in combination, concave and convex members, a die provided with a U-shaped cutting edge and a pair of heel breast shoulder forming edges, one of said members being yieldingly supported by the die, and means to effect relative movement of the die and said one member on one hand and the other member on the other hand to flex the heel end of the sole and then to remove material from the marginal portion of the heel end of the sole by a beveling cut and to form heel breast receiving shoulders on the sole.

8. A heel-seat-fitting machine having, in combination, members constructed and arranged respectively to engage the opposite sides of a sole positioned in the machine, a die provided with a U-shaped cutting edge and a pair of heel breast shoulder forming edges, one of said members being yieldingly supported by the die, and means to effect relative movement of the die and said one member on one hand and the other member on the other hand in a path disposed at substantially right angles to the plane of the sole to flex the heel end of the sole and then to remove material from the marginal portion of the sole by a beveling cut and to form a pair of heel breast receiving shoulders on the sole.

9. A heel-seat-fitting machine having, in combination, a convex member, a die provided with a U-shaped cutting edge and having at each side of said edge a cutting edge extending laterally of the U, a concave member carried by but yieldable relatively to the die included within the U-shaped cutting edge, and means to operate the die to cause the members to deform the heel portion of a sole and to cause the die to cooperate with the convex member to reduce said portion of the sole and to form laterally extending shoulders on the same.

10. A heel-seat-fitting machine having, in combination, a convex member, a die provided with a U-shaped cutting edge and having at each side of

said edge a cutting edge extending laterally of the U and at an angle to the plane of the U-shaped cutting edge, a concave member carried by but yieldable relatively to the die included within the 5 U-shaped cutting edge, and means to operate the die to cause the members to deform the heel portion of a sole and to cause the die to cooperate with the convex member to reduce said portion of the sole and to form laterally extending shoulders 10 on the same.

11. A heel-seat-fitting machine having, in combination, convex and concave members, a die provided with a U-shaped cutting edge and a pair of heel breast shoulder forming edges, said die being 15 mounted for movement relatively to the convex member, said concave member being mounted for movement with the die and also being mounted for yielding movement relatively to the die, and means to move the die and the concave member 20 relatively to the convex member to cause the members first to distort the heel seat portion of a sole and then to cause the die to cooperate with the convex member to remove the margin of the heel seat portion and to form a pair of heel breast 25 receiving shoulders on the sole thereby to shape the same for the reception of a heel.

12. A heel-seat-fitting machine having, in combination, a member provided with a convex surface and having a step projecting therefrom, a 30 concave member shaped to include said surface and mounted for movement relatively to the first-named member to distort the rear end of a sole, and a die mounted for movement past said step to trim material from the margin of the rear end of 35 the distorted sole by a beveling cut.

13. A heel-seat-fitting machine having, in combination, means to position a sole, a block provided with an ellipsoidal surface, a presser member having a cavity constructed and arranged to 40 receive said surface, and a die provided with a U-shaped cutting edge and a pair of heel breast shoulder forming edges, said die being constructed and arranged to carry said presser member and being mounted for movement relatively to said 45 block along a path disposed at substantially right angles to the plane of the positioned sole for causing the presser member to cooperate with the block to distort the heel seat portion of the sole and for causing said die to remove the margin of 50 said heel seat portion of the sole by a beveling cut as well as to form heel breast receiving shoulders on the sole.

14. A heel-seat-fitting machine having, in combination, concave and convex members, a die provided with a U-shaped cutting edge and a pair 55 of cutting edges extending transversely of said edge at opposite sides of the same, one of the members being mounted for movement relatively to the other to flex the rear end of a sole, and the die being mounted for movement to cooperate with one of said members thereby removing the margin of the rear end of the sole by a beveling cut and forming shoulders with which the breast of a heel abuts.

65 15. A heel-seat-fitting machine having, in combination, convex and concave members, a die provided with a U-shaped cutting edge and a pair of cutting edges extending transversely of and removed from the ends of the U-shaped cutting 70 edge, one of said members being mounted for movement relatively to the other to flex the rear end of a sole and the die being mounted for movement relatively to said other member to form a tongue at the rear end of the sole and also to 75 form a pair of tabs extending rearwardly from

the breast line of the sole at opposite sides of the tongue.

16. A heel-seat-fitting machine having, in combination, a convex member, a concave member, a die constructed and arranged yieldingly to support the concave member and provided with a U-shaped cutting edge, and a pair of cutting edges extending transversely of said U-shaped cutting edges from opposite sides of the U, said die and said concave member being mounted for movement relatively to the convex member to cause the concave member to wrap a sole around the convex member and then to cause the die to remove the margins of the rear end of the sole by a beveling cut and to form shoulders against which the breast of a heel positioned upon the sole abuts. 80 85 90

17. A heel-seat-fitting machine having, in combination, a concave member, a convex member provided with a U-shaped edge and a pair of laterally extending notches, a die provided with a U-shaped cutting edge and with a pair of cutting edges extending transversely at opposite sides of said U-shaped cutting edge, said die and said concave member being mounted for movement relatively to the convex member for cooperating with the U-shaped edge to remove the margins of the rear portion of a sole by a beveling cut and to cause the laterally extending cutting edges to engage the notches thereby removing material trimmed from the sole by said U-shaped cutting edge and forming laterally extending shoulders on the sole. 95 100 105

18. A heel-seat-fitting machine having, in combination, means to position a sole, a member having a dished surface open at one end, a block provided with a dome, and a die constructed and arranged yieldingly to carry said member mounted for movement relatively to said block to cause the dished surface to wrap the heel end of the sole around the dome and then to cause the die to trim the margins of the heel end of the sole by a cut inclined to the plane of the sole. 110 115 120

19. A heel-seat-fitting machine having, in combination, means to position a sole, a U-shaped die, a member having a dished surface open at one end carried by the die and yieldingly movable relatively thereto, a block provided with a dome, and mechanism to move the member relatively to the block thereby causing said dished surface to wrap the heel end of a sole around the dome and then to move the die against the block thereby trimming the margin of the heel end of the sole to shape the same for receiving a heel. 125 130 135

20. A heel-seat-fitting machine having, in combination, means to position a sole, a presser having a dished surface, a member provided with a dome surface, a die provided with a U-shaped cutting edge and having a guideway to receive said presser, resilient means normally to urge the presser beyond the U-shaped cutting edge, and mechanism to limit the movement of the presser beyond said cutting edge, said die and said presser being mounted for movement toward said member thereby causing the dished surface to wrap the heel end of the sole around the dome surface and causing the U-shaped cutting edge to pass through the distorted portion of the heel end of the sole to trim the margin of the heel end by a beveling cut. 140 145 150

21. A heel-seat-fitting machine having, in combination, a table provided with a face to support a sole, means to position the sole upon said

face, members relatively movable in a path disposed at substantially right angles to the face of the table to distort the heel end of the sole, and a die movable in a path disposed at substantially right angles to the table against one of the members to remove the marginal portions of the heel end of the distorted sole to shape the same for receiving a heel, said table being yieldingly mounted for movement in a path extending at substantially right angles to said face thereby relieving the strain on the sole during the sole distorting and trimming operation.

22. A heel-seat-fitting machine having, in combination, a convex member provided with a U-shaped edge and a pair of notches extending laterally of and at an angle to the plane of said edge, a concave member, a die constructed and arranged yieldingly to support the concave member and having a U-shaped cutting edge and a pair of cutting edges extending laterally of the U-shaped cutting edge and at an angle to the plane of said edge, said die and said concave member being mounted for movement relatively to the convex member thereby causing the concave member to wrap the heel portion of a sole around the convex member and causing the U-shaped cutting edge of the die to cooperate with the U-shaped edge of the convex member to trim the margin of the heel portion of the sole with a beveling cut as well as to cause the laterally extending cutting edges to enter the notches to form laterally extending shoulders upon the sole.
